(57) **CLAIM**

The ornamental design for a polyhedral die, as shown and described.

DESCRIPTION

FIG. 1 is a first perspective view of a polyhedral die embodying the claimed design.

FIG. 2 is a second perspective view of the polyhedral die shown in FIG. 1.

FIG. 3 is a third perspective view of the polyhedral die shown in FIG. 1; and,

FIG. 4 is a fourth perspective view of the polyhedral die shown in FIG. 1.

The dash-dot broken lines immediately adjacent to and surrounding the golf indicia disposed on the shaded surfaces of the polyhedral die represent the bounds of the claimed design while dash-dash broken lines represent edge portions of the polyhedral die; the broken lines form no part of the claimed design.
